ELECTRIC CIRCUIT BREAKER

Charles Bresson, Lyon, France; vested in the
Alien Property CustodianApplication June 26, 1940, Serial No. 342,569
In Luxembourg June 27, 1939

2 Claims. (Cl. 200—89)

1

This invention relates to electric circuit breakers, and more particularly to a mechanism which causes the current interrupting means, following their separation responsive to the occurrence of a fault in the electric system protected, to be reclosed extremely rapidly.

One of the objects of the invention is to reduce the amount of energy required for such reclosing of the current interrupting means.

Another object of the invention is to provide an apparatus for reclosing the current interrupting means in an electric breaker, which comprises a mechanism for storing up potential energy during the separation of the current interrupting means, and redelivering said energy as additional energy for the reclosing of said current interrupting means. The stored energy is obtained from the kinetic energy of the movable parts of the circuit breaker.

The invention, the aforesaid object thereof, and such other aims and objects as may herein-after appear, will be readily understood from the following description, taken in connection with the accompanying drawings of one embodiment of the invention herein given for illustrative purposes, the true scope of the invention being more particularly pointed out in the appended claims.

Referring to the drawings:

Fig. 1 is a vertical sectional view partly in elevation and partly diagrammatic of a circuit breaker, and an operating column therefor, and operating connections between the column and the movable contact of the breaker.

Fig. 2 is a top plan view of means for turning the operating column of Fig. 1 together with a diagrammatic circuit arrangement for controlling such means.

Figs. 3 and 4 are diagrammatic views showing certain of the operating parts in different operating positions.

Fig. 5 is a detailed view, partly in elevation and partly broken away, showing a gearing connection between the column and the contact operating mechanism, and

Fig. 6 is a detailed view of a time lag device for controlling the reclosing of the circuit breaker contacts.

The invention is herein shown in its application to a polyphase circuit breaker, but it is understood that it is not to be considered as limited to said particular application. Said polyphase circuit breaker comprises a normal or main circuit breaker A (see Fig. 2) having connected in series therewith an ultra-rapid circuit breaker B which, upon the occurrence of a fault, acts

immediately to break the circuit of the electric system to be protected, viz: in that phase only which is affected by said fault, and thereafter recloses said circuit, before the normal or main circuit breaker A having a slow or delayed operation has time to operate. Said normal circuit breaker A is actuated to definitely break said circuit only in the event that the fault persists.

The circuit interrupting means of breaker B 10 comprises a stationary contact C₂ (see Fig. 1) and a movable contact lever, the latter consisting of a rod C which passes through an arc drawing chamber D and is actuated by suitable means, such as a lever L₁, fulcrumed upon a fixed shaft 15 L₂ mounted in the frame C_t of the apparatus. Said lever L₁ is pivotally connected to the upper end of said movable contact C by a short link I, and intermediate its ends, i. e. at P, is pivoted thereto one end of a link B_e, whose other end 20 is pivotally connected at P₁ to the one end of a double lever P₃ freely fulcrumed upon a horizontal shaft T and having its other end formed as a nose L₅. An intermediate member or actuator E is splined upon said horizontal shaft T 25 adjacent said lever P₃ and carries a stop-stud L₆. Said nose L₅ abuts the stop-stud L₆ due to the action of an energy storing spring R₁ on said double-lever P₃, said spring R₁ being connected between said pivot P₁ and a stud P₂ of said actuator E. Said spring R₁ stores up energy, when the contact C is withdrawn from contact C₂ and redelivers said energy subsequently to accelerate the movement of the movable contact C, when the circuit to be protected is reclosed. This will be 30 35 fully explained hereinafter.

Said actuator E is operatively connected to a rotary column I by means of a beveled gear g₂ mounted on the upper reduced end I₂ of said column I (see Fig. 5) and engaging a beveled gear g₃ secured on said horizontal shaft T which is rigidly fastened to actuator E. Upon the lower reduced end I₁ of said column I which is adapted to rotate in suitable bearings located at both ends, is rigidly secured a crank arm Mg (see Fig. 2). 40 45 The bearings of column I may be of any suitable conventional structure and are omitted in Fig. 1 of the drawings in order not to encumber the latter unnecessarily. A cam Ca engaging said crank Mg is mounted to rotate around a vertical shaft V (see Fig. 2). When the movable contact C is in engagement with the stationary contact C₂, shown in Fig. 1, said crank Mg and said cam Ca are in the positions shown in Fig. 2 and further rotation of said cam Ca counter-clockwise, i. e. in the direction of arrow f₁ is stopped

as a nose *b* of said cam *Ca* abuts a stop roller *R2* supported by one end of an arm *Ld* pivoted at *P* to the frame of the apparatus. Said arm *Ld* is operatively connected to a toggle comprising two links *l₃*, *l₄*, one of which is pivoted to said arm *Ld*, and the other to the frame of the apparatus. A gear *u*, only a segment of which is shown in Fig. 2 in order not to complicate the drawings, is connected at *S3* to one end of a spiral spring *S*, whose other end is attached to said cam *Ca* at *S2*, so that upon rotation of said gear *u* counter-clockwise, said spring *S* will be tensioned and cause said cam *Ca* to swing also counter-clockwise to rotate said crank arm *Mg* in the direction of arrow *f₁* when said toggle *l₃*, *l₄* is broken. In other words after release of said cam *Ca* due to the breaking of toggle *l₃*, *l₄*, cam *Ca* and therewith crank *Mg* are rotated under action of said spring *S*. As a result of this, contact *C* is separated from contact *C₂*, as will be fully explained hereinafter. Said gear *u* is driven by an electric motor *Mo* through a worm *W* and tensions said spring *S*, when said contacts *C* and *C₂* are closed and said cam *Ca* is locked against further counter-clockwise rotation by engagement of nose *b* with said stop roller at *R2*.

During its counter-clockwise movement, said cam *Ca* engages said crank *Mg*, whereby it swings the latter in the direction of arrow *f₂* in Fig. 2 which causes contact *C* to move away from contact *Ca* within the arc-drawing chamber *D*, whereupon said crank *Mg* engages a stop *Lr*, and is temporarily locked by the latter against further movement (see position of crank *Mg* indicated with a dotted line in Fig. 2). Said stop arm *Lr* is pivoted at *P5* to the frame of the apparatus and connected to said frame by a two-link toggle *Lc* which is similarly constructed as toggle *l₃*, *l₄* above described. A piston *Pr* is operated after a certain time interval to break said toggle *Lc* and thereby release said crank *Mg* so that it can cause said movable contact *C* to move towards the stationary contact *C₂* and thereby close the circuit to be protected. Said piston *Pr* is actuated and controlled for this purpose by a retarding or time lag device *DM*.

Said devices *DM* and *Pr* control the reclosing of the circuit breaker contacts each time after said contacts have been separated and after a certain period of time has elapsed. Such intervals are necessary for the deionization of the air at the place where the fault occurred in the circuit to be protected by the circuit breaker.

The retarding or time lag mechanism *DM* and piston *Pr* actuated by said time lag device are shown in detail in Fig. 6. The time lag of said retarding mechanism can be varied, whereby the time interval between the breaking of the circuit and its reclosure can be adjusted according to the requirement of the network. The retarding mechanism shown in Fig. 6 operates as follows:

When during the contact separating movement crank *Mg* swings in the direction of the arrow *f₂*, its upper arm *N* is withdrawn from a lower arm of a double-lever *l₂* of the retarding mechanism *DM*. Said double-lever *l₂* swings around the same pivot *l₆* as a gear sector *l₇* which is pulled by a main spring *l₈* in the direction of arrow *f₉*. A train of gears *20* including a first gear *21* having a ratchet wheel *22* is in engagement with the gear sector *l₇*. Said train of gears *20* is under control of an escapement *23* which permits the gears to turn but in exactly timed continuously interrupted intervals in a manner well known. The double-lever *l₂* and

the gear sector *l₇* are operatively linked to each other by a short spring *24* in such a manner that the lever *l₂* will follow the movements of the gear sector *l₇*, when the latter is moved in the direction of the arrow *f₉*. As the gear sector *l₇* is in engagement with the train of gears *20* controlled by the escapement *23*, the turning of said sector and of double-lever *l₂* occurs also in exactly measured timed intervals. In the last position of the double-lever *l₂*, its upper arm strikes a catch *l₃*, which then releases a shorter arm *l₈* of a crank-lever *l₄*, the latter being operatively connected to the piston *Pr* through a link *l₅*. Thus, as a result of the release of the crank-lever *l₄*, the piston *Pr* is released and is pushed downwards by a spring *2* placed over the piston rod and acting on the piston *Pr*, which breaks the toggle *Lc* whose function has been described above. During the contact closing of the circuit breaker, the upper arm *N* of said crank *Mg* swings in the opposite direction, as indicated by arrow *f₂* and thereby turns the double-lever *l₂* in the direction of the arrow *f₃*. As a result of this, double-lever *l₂* pulls the gear sector *l₇* with the aid of the short spring *24* in the opposite direction of arrow *f₉*, whereby the main spring *l₈* is tensioned. The ratchet wheel *22* allows the movement of the gear sector *l₇* in the opposite direction of arrow *f₉* without interference of the train of gears *20* and action of the escapement *23*. During said movement, the upper arm of double-lever *l₂* returns the crank *l₄* in the initial position in which the shorter arm *l₈* of crank lever *l₄* is held by the catch *l₃*.

The gear sector *l₇* has a stop *l₂₅* which limits the rotation of said gear sector *l₇*, when the latter is turned in the opposite direction of arrow *f₉*, i. e. when the main spring *l₈* is tensioned. During this movement, said stop *l₂₅* engages the lower part of a timing lever *l₇* fulcrumed at the same pivot *l₆* as crank-lever *l₄*. A dial *27*, for example graduated in seconds indicating the time lag, is provided opposite the upper end of said timing lever *l₇*. By simply changing at will, the position of the timing lever *l₇* with respect to the dial graduation *27* the abutment for the stop *l₂₅* of gear sector *l₇* at the lower part of the timing lever *l₇*, can be shifted, whereby the actuating time of the retarding mechanism *DM* is varied. Instead of the described retarding device any other mechanism of this type may be effectively used.

In the electric diagram of the new circuit breaker, illustrated in Figure 2, a transformer *T₁* is provided, whose primary is supplied with electric energy of the circuit to be protected by the circuit breakers *A* and *B* from a suitable alternating current source through mains *M1* and *M2*.

In the normal operation of the system, the parts of the circuit breakers are in the positions shown in Figures 1 and 2 and the contacts *C* and *C₂* of circuit breaker *B* are closed. If now a fault occurs in the circuit to be protected, said transformer *T₁* through its secondary actuates a relay *R* and thereby closes a circuit through a coil of an ultra-rapid two-point switch *CUR*. As a result of this the latter switch *CUR* is actuated and a circuit through a coil *BB* is thereby closed causing an armature *BB₁* controlled by coil *BB* to move upwardly and break the toggle *l₃*, *l₄*. Thereby, lever *Ld* is moved to the left and releases cam *Ca*. The latter now rotates under the action of spring *S* in the direction of arrow *f₁* and thereby swings crank *Mg* in the direction of arrow *f₂*. Crank *Mg* rotates column *I* (see

Fig. 1) clockwise, and said column through the gears g_2 and g_3 (see Fig. 5) rotates shaft T and thereby swings actuator E rigid on shaft T counter-clockwise to break the circuit to be protected by moving the movable contact C upwardly with the aid of the connecting links and levers above described. When the position of the actuator E, shown in Fig. 3 is about to be reached, movements of lever L_1 , short link l , and movable contact C will be slowed down, as the system comprising link Be and lever P_3 is approaching its dead-center and lever L_1 is moved proportionately with respect to the movement of said link Be. Simultaneously, the rotary movement of column I is accelerated, as the crank Mg in contact with cam Ca has its operative edge so shaped that such movement is produced. When the lever P_3 contacts a stop B_t , the system comprising lever P_3 , link Be, lever L_1 and movable contact C is stopped, but column I although not acted upon by cam Ca at this phase of operation continues to rotate on account of the impulse that it has previously received. This continued rotation of said column is transmitted to the actuator E, whereby on account of the mentioned stoppage of lever P_3 and of the members linked thereto the spring R_1 will be tensioned, as shown in Fig. 4. The energy stored up by column I during the first phase of its accelerated movement is thus transferred to said spring R_1 whereby the movement of column I is slowed down. Thus, spring R_1 is strongly tensioned and accumulates the potential energy resulting from the kinetic energy of column I. When column I reaches its end position, crank Mg takes the position indicated in dotted lines in Fig. 2. In said position crank Mg is locked by the stop arm L_r .

During the rotation of cam Ca, the latter strikes at the proper time a two-point break T_a , which then interrupts the circuit through coil BB so that armature BB cannot break the toggle l_3 , l_4 . Said two-point break T_a is operatively connected to a mechanical time delayed actuator RM of any suitable conventional construction, which is adapted to automatically reclose said circuit after a certain time interval has elapsed, i. e. after the extinction of the arc drawn, which is in practice approximately 15 seconds, in order to prevent the circuit from being broken twice in rapid succession in the same arc drawing chamber D.

The reclosure of the contacts of switch B after release of crank Mg takes place as follows: In the beginning of the circuit breaking movement of the movable contact C, the upper arm N of crank Mg contacts the above described time-lag relay DM and sets it in operation. Upon the elapse of time, for which said time-lag relay is adjusted, piston P_r is released by the time-lag relay DM, and the toggle L_c is broken by piston P_r . As a result of this, lever L_r withdrawn to release crank Mg and spring R_1 can now re-deliver its energy which it has stored up during the contact separating movement of the movable contact C. Spring R_1 causes the actuator E to swing in the direction of arrow f_4 of Fig. 4, whereby stop-stud L_6 of said actuator contacts nose L_5 of double-lever P_3 and swings the latter in the direction of arrow f_5 . As link Be is operatively connected to lever P_3 , said link is moved downwards and together with it the free end of lever L_1 linked to the movable contact C. The movement of said contact C is accelerated as above described, and when said contact is about to close

the circuit, its closing movement is damped by a conventional hydraulic damper A_h .

If upon closing of the circuit breaker B, the fault which caused the circuit breaker to interrupt the circuit to be protected has disappeared, the circuit of coil BD will remain broken by the contacts of relay RR, whose action is sufficiently retarded. The operating circuit of said relay RR is broken by the ultra-rapid two-point switch CUR, and the main circuit breaker A will then not be actuated to break the circuit. If however, the fault should persist, relay R and consequently the two-point switch CUR will automatically operate to cause relay RR to close the circuit of coil BD with the result that the main circuit breaker A is actuated to definitely interrupt the circuit.

The present invention enables all the energy used for separating the contacts of circuit breaker B to be stored on the conclusion of the circuit interrupting operation and to be re-utilized for the rapid reclosure of the main circuit by said circuit breaker B. Consequently, a much smaller motor M_0 than heretofore required can be used, whereby the same speed for the closure is secured. By reducing the energy to be stored in spring S, the power of the motor M_0 can be reduced by the same amount, while a speed of operation is obtained which is comparable to that heretofore obtained with circuit breakers using much more powerful motors without having means for storing the energy during the opening movement.

I am aware that the present invention may be embodied in other specific forms without departing from the spirit or essential attributes thereof, and I therefore desire that the present embodiment of the invention be considered in all respects as illustrative and not restrictive.

I claim:

1. In an electric circuit breaker, fixed and movable contacts, means to actuate said movable contact to break the circuit by moving said movable contact away from said fixed contact, said means comprising a rotary column, a spring operatively connected between said column and said movable contact, a stop to arrest the movement of said movable contact when the latter reaches the end of its circuit breaking stroke, whereby continued rotation of said column is retarded by the resultant tensioning of said spring, means adapted to release said spring to cause it to re-deliver its stored energy to allow said movable contact to move towards said fixed contact to close the circuit, and a time lag device controlling the release of said spring.

2. In an electric circuit breaker, comprising a fixed and a movable contact in the circuit to be protected by said breaker, operating means being constructed and arranged to actuate said movable contact to break the circuit, means for storing up energy during the circuit breaking operation, said operating means comprising a cam, a crank driven by said cam, and a toggle mechanism, said toggle mechanism being adapted to lock said movable contact in its open position after completion of the separating movement of said contact, means to break said toggle mechanism, and a timing device adapted to actuate said breaking means after a predetermined time lag to free said crank and thereby allow said means for storing energy to cause the closing movement of the movable contact.

CHARLES BRESSON.
